DESIGN FOR A COMBINED COMB, RAZOR, AND RULE

Vincent R. Pileggi, Philadelphia, Pa.

Application March 30, 1944, Serial No. 113,088

Term of patent 14 years

(CL. D86—8)

To all whom it may concern:

Be it known that I, Vincent R. Pileggi, a citizen of the United States, residing at Philadelphia, in the county of Philadelphia and State of Pennsylvania, have invented a certain new, original, and ornamental Design for Combined Comb, Razor, and Rule, of which the following is a specification, reference being had to the accompanying drawing, forming part thereof.

In the drawing:

Fig. 1 is a side elevational view of a combined comb, razor, and rule embodying my new design.

Fig. 2 is an end elevational view of the device illustrated in Fig. 1 on an enlarged scale.

I claim:

The ornamental design for a combined comb, razor, and rule, substantially as shown.

VINCENT R. PILEGGI.
